Des. 218,190

Patented July 28, 1970

218,190

HOT TRAY LIFTER

James Demetreon, Kansas City, Mo., assignor to Handi Caddy Inc., a corporation of Missouri

Continuation-in-part of design application Ser. No. 14,555, Nov. 20, 1968. This application Apr. 9, 1969, Ser. No. 16,642

Term of patent 14 years

U.S. CL. D44—4

Fig. 1.

Fig. 2.

Fig. 3.

FIG. 1 is a perspective view of a hot tray lifter showing my new design;

FIG. 2 is a top plan view; and

FIG. 3 is a side elevational view.

This is a continuation-in-part of my earlier filed application Ser. No. D. 14,555 of Nov. 20, 1968.

I claim:

The ornamental design for a hot tray lifter, as shown and described.
